UNITED STATES PATENT OFFICE.

ALEXANDER H. HILL, OF OSKALOOSA, IOWA.

SCHOOL-DESK INKSTAND.

SPECIFICATION forming part of Letters Patent No. 319,815, dated June 9, 1885.

Application filed December 15, 1884. (Model.)

To all whom it may concern:

Be it known that I, ALEXANDER H. HILL, of Oskaloosa, in the county of Mahaska and State of Iowa, have invented certain new and 5 useful Improvements in School - Desk Inkstands; and I do hereby declare that the following is a full, clear, and exact description thereof, reference being had to the accompanying drawings, and to the letters of reference 10 marked thereon, which form part of this specification.

The object I have in view is to provide an ink-receptacle to be used in connection with school-desks, the said receptacle being of such 15 construction and arrangement that the objections which have hitherto obtained with respect to this class of devices will be wholly obviated—such, for instance, as the great waste of ink by reason of its evaporation, and the 20 noise incident to the covering or uncovering the receptacle therefor, which, though not noticeable in one or two instances, yet when many times multiplied (as in the case of a large school) becomes an expense and annoyance of no little moment.

The improvements which I have made will be clearly understood from the following description, when taken in connection with the 25 annexed drawings, in which—

30 Figure 1 is a central longitudinal section with the hinged cap down; Fig. 2, a plan view of the ink-bottle frame, showing a central section of the top raised, being shown in inverted position; Fig. 3, a plan of the whole device 35 when closed; Fig. 4, a similar view with the adjustable cap removed, thus exposing the cork or rubber. Fig. 5 is a view of the cap itself. Fig. 6 is a bottom view.

Similar letters of reference denote corresponding parts.

A represents a circular metal frame of suitable size, which is cast with ears *a a*, through which are holes for the purpose of securing the frame to the school-desk. The frame A 45 is also cast with a projection, *b*, which has upon its outer end and at right angles thereto ears *c c*, between which the lid is hinged, as will be fully seen hereinafter. *d d* are small projections cast upon the inner circumference 50 of the frame, the object of which will be presently more fully seen.

B represents a metal lid, which consists of

a ring-like device having a neck, *e*, through which is a hole, and by means of which it is pivoted or hinged between the ears *c c*. The 55 end of this neck should have a small projection or stop, in order to prevent it from falling back, and may be provided with a cushion to obviate the noise when thrown open.

The inner bottom part of the lid or ring B 60 is cast with seats or flanges *g g*, upon which rests a disk of cork, rubber, or other suitable material, *a'*. The inner circumference of the lid B should slightly flare upwardly, so that the cork or rubber disk *a'* may be more readily inserted. *h h* are small projections cast upon the outer side of lid B near its top, and between the ends of the flanges thereon, or rather centrally and above the spaces left between the flanges *g g*.

70 C represents an adjustable cap, the rim of which should fit in the top of lid B and rest upon the cork or rubber disk-stopper *a'*. The circumference of the rim should have notches *i i*, to register with the projections *h h*, and 75 one side of each of these notches should be beveled or inclined, so that when the cap is placed upon the disk it may be turned and by means of the projections *h h* forced down securely upon the rubber disk or stopper *a'*. It 80 will thus be seen that when the cork becomes hard or unyielding it may easily be replaced by a fresh one.

D represents the ink - bottle, (preferably made of glass,) which is made with a circular 85 flange, *K*, a little below its mouth or top. This flange is of such circumference as to allow it to rest within the frame A and upon its projection *d d*. A short distance below the flange *K* are cast or formed the projections *K' K'*, of less circumference than the flange above them, and with sufficient space 90 between their ends to admit of the projections *d d* passing.

A suitable hole having been made in the 95 desk and the frame properly secured over it, the bottle D is adjusted so that projections *d d* will pass between the ends of the projections *K' K'*. Then by turning the bottle it will be securely held in place.

100 If found necessary, I contemplate the employment of a suitable spring to press the cap or cork tightly upon the ink-bottle.

Thus it will be seen from the foregoing that

I provide a school-desk with an ink-receptacle that will obviate noise, loss of ink by evaporation, and withal one that cannot be readily broken or displaced.

5 Having described my invention, I claim as new—

1. The combination, with a circular frame, A, having the ears *a*, for attachment to the desk, and provided with the projection *b*, having the ears *c*, of the circular lid B, provided with the neck *e*, which pivots between the ears *c* and boxing, the flanges *g*, bearing against the under surface of the stopper *a'*, and a removable cap secured to the upper surface of the lid B, to hold the stopper in place, substantially as described.

15 2. The combination, with the circular lid B, provided with the flanges *g* and projec-

tions *h*, of the stopper *a'*, secured in the lid by the cap C, provided with the notches *i*, having beveled edges, substantially as specified.

20 3. The combination of the circular frame A, adapted to be secured to the desk, and the ink-well D, connected therewith, with the lid B, hinged to the circular frame A, and having the stopper *a'* secured in the lid by the detachable cap C, substantially as specified.

25 In testimony that I claim the foregoing as my own I affix my signature in presence of two witnesses.

ALEXANDER H. HILL.
